UNITED STATES PATENT OFFICE.

ADELARD CARAND DAUPHINAIS AND DOMINIQUE GARON, OF CÔTE ST. PAUL, CANADA; SAID DAUPHINAIS ASSIGNOR TO SAID GARON.

CLIPPER.

SPECIFICATION forming part of Letters Patent No. 665,069, dated January 1, 1901.

Application filed February 21, 1900. Serial No. 6,124. (No model.)

To all whom it may concern:

Be it known that we, ADELARD CARAND DAUPHINAIS and DOMINIQUE GARON, subjects of Her Majesty the Queen of Great Britain, residing at Côte St. Paul, county of Hochelaga, Province of Quebec, Canada, have invented certain new and useful Improvements in Clippers; and we do hereby declare that the following is a full, clear, and exact description of the invention, such as will enable others skilled in the art to which it appertains to make and use the same.

This invention relates to clippers, and one object is to provide clippers which may be adjusted so as to cut the hair at a predetermined length.

A further object is to provide clippers with an adjusting mechanism for regulating the length at which the hair is to be cut, which is simple in construction, effective in operation, and which may be manufactured at a moderate cost.

To these ends the invention consists in an adjustable clipper constructed substantially as herein illustrated and described and defined in the appended claims.

Referring to the drawings, in which similar letters of reference indicate similar parts, Figure 1 is a view in perspective of a pair of clippers constructed in accordance with this invention. Fig. 2 is a front view thereof; and Fig. 3 is a rear view, parts being broken away.

In the drawings, A and A' represent the lever members of a pair of hair-clippers constructed in any usual or preferred form and having the usual fixed cutting-plate a and the movable cutting-plate a' . The base-plate a^2 , to which is rigidly connected the fixed lever member A and within which is pivoted the movable lever member A', is provided with a bracket B, in which is journaled the vertical adjusting screw-rod B', the lower end of which is swiveled in the base-plate a^2 . Within the bracket B is the ratchet-disk b , which is fixed upon the rod B'. A lever B ^{2} is journaled within the bracket B to the lower end of the screw-rod B' and is removably connected at its handle end by means of a pin-and-slot connection with the movable lever member A'. The other end of the lever B ^{2} car-

ries a spring-pressed pawl b' , which engages and operates the ratchet-disk b when the movable lever member A' is operated. A spring-stop b^2 is connected to the base-plate a^2 and 55 engages the teeth of the ratchet-disk b to prevent the backward rotation of said disk.

A cross-bar D is loosely sleeved upon the upper portion of the screw-rod B' and is provided at its ends with the downwardly-extending rods d , which are guided through openings in lugs d' , formed upon the base-plate a^2 . A spiral spring d^2 is sleeved upon each of the rods d and bears against the lugs d' and the cross-bar D to return the cross-bar D to its normal position. To the lower end of the rods d is secured the adjusting-plate D', which is substantially the same shape, size, and construction as the fixed cutting-plate a , beneath which the adjusting-plate is arranged. Pivotedly connected to the cross-bar D is a spring-operated adjusting-lever D ^{2} , having a suitable handle at one end and near its other end an inclined plate d^3 , which is adapted to be normally held in 65 engagement with the thread of the screw-rod B'. The usual spring C is connected at one end to the base-plate a^2 and at the other end to the movable lever member A'.

Upon operating the lever members the 80 ratchet mechanism will cause the screw-rod B' to lower, carrying with it the adjusting-plate D', thus permitting the cutting of the hair at a gradually-increasing length. In order to lower the screw-rod B' for the purpose 85 of adjusting the adjusting-plate D', it is necessary for the plate d^3 to engage with the spiral groove in the screw-rod B', said plate serving as a fixed point of resistance for said screw-rod, because it is fast on the lever D ^{2} . 90 In the operation of the implement the lever members A A' are drawn together and forced apart alternately in the ordinary way for the purpose of reciprocating the cutter-plate having the comb-teeth over the fixed cutter-plate also provided with the comb-teeth, and during this operation of the lever members the lever B ^{2} moves with the lever member A' for the operation of the ratchet mechanism and to effect the rotation of the screw-rod, 95 the plate d^3 of the lever D ^{2} serving as the means for depressing this screw, whereby the adjust-

ing-plate D', having the comb-teeth, will be positively and automatically moved away from the fixed comb-plate. During this depression of the adjusting-plate the guide-
5 rods are drawn downwardly therewith, so as to lower the cross-rod D on the screw-rod, and the coiled springs, which rest upon the lugs d' of the bracket B, are compressed so as to be placed under tension and act against the cross-bar D. The lever D² may be shifted on its fulcrum on the cross-bar D, so as to disengage the plate d³ from the spiral groove in the screw-rod, whereupon the coiled springs become active to quickly lift the cross-bar D, 10 which through the guide-rods serve to raise the adjusting-plate and the screw-rod to their elevated positions, whereby the plate D' is drawn into contact with the under side of the fixed cutter-plate, so that the comb-teeth on 15 the adjusting-plate will register with the comb-teeth on the fixed cutter-plate.

To operate the implement as an ordinary clipper, the spring-lever B² is disconnected from the movable lever member A', thus 20 throwing the ratchet feed mechanism out of operative connection with said movable lever member.

While we have herein shown a preferred form of carrying our invention into effect, 25 yet we do not desire to limit ourselves to such preferred details of construction, but claim the right to use any and all modifications thereof which will serve to carry into effect the objects to be attained by this invention in so far as such modifications and changes may fall within the spirit and scope 35 of our said invention.

We claim—

1. A hair-clipper comprising fixed and movable cutter-plates, lever members therefor, an adjusting-plate in adjustable relation to the fixed cutter-plate, a screw-rod connected to the adjusting-plate, ratchet feed mechanism in operative relation to the screw-rod and one 40 of the lever members, a lever having a fixed point of resistance in shiftable relation to the screw-rod, and means for retracting the screw-rod and adjusting-plate on the disengagement of the fixed point of resistance from said 45 screw-rod, substantially as described.

2. A hair-clipper comprising fixed and movable cutter-plates, lever members therefor, an adjusting-plate in adjustable relation to the fixed cutter-plate, a rod connected to the adjusting-plate, the ratchet mechanism having 50 operative connection with a lever member and said screw-rod, a cross-bar slidably fitted to the screw-rod and connected to the adjusting-plate, a lever mounted on the cross-bar and

having a plate engaging with the groove of 60 the screw-rod, and coiled springs in operative relation to the cross-bar to lift the latter and the adjusting-plate on the release of the lever and its plate from the screw-rod, as set forth.

3. A hair-clipper comprising the fixed and 65 movable cutter-plates, lever members therefor, an adjusting-plate, a screw-rod connected with said plate, a ratchet fast with the screw-rod, a spring-lever sleeved on the screw-rod and having detachable connection with the 70 movable lever member, a feed-pawl carried by the spring-lever and engaging with the ratchet, and a fixed point of resistance for the screw-rod, substantially as described, for the purpose set forth. 75

4. A hair-clipper comprising fixed and movable cutter-plates, lever members therefor, a bracket fast with the fixed plate and one lever member and provided with suitable guide-lugs, an adjusting-plate, a ratchet feed mechanism having operative connection with the movable lever member, a screw-rod connected to the adjusting-plate and made fast with the ratchet of the feed mechanism, a cross-bar 80 slidable on the screw-rod, rods connecting the 85 adjusting-plate and the cross-bar and slidable in the lugs of the bracket, springs fitted on the rods and seated against the lugs and the cross-bar, and a lever fulcrumed on the cross-bar and having a plate which engages with 90 the groove of the screw-rod, substantially as described.

5. A clipper comprising a base-plate; a lever member fixed thereto; a movable lever member pivotally connected therewith; a cutting-plate fixed to said base-plate; a movable cutting-plate pivotally connected with said 95 movable lever member; a bracket mounted upon said base-plate; an adjusting-screw journaled in said bracket; a pawl and ratchet connected with said screw; a cross-bar slidably mounted upon said screw; an adjusting-plate connected with said cross-bar, retracting-springs for returning said adjustable plate to its normal position; a spring-pressed lever 100 pivoted to said cross-bar and adapted to be moved into and out of engagement with said adjusting-screw; and a lever secured to said ratchet mechanism and adapted to be detachably connected with said movable member, 105 substantially as described. 110

In witness whereof we have hereunto set our hands in the presence of two witnesses.

ADELARD CARAND DAUPHINAIS,
DOMINIQUE GARON.
